[57] CLAIM

The ornamental design for a decanter, substantially as shown.

DESCRIPTION

FIG. 1 is a front elevational view of a decanter showing my new design;
 FIG. 2 is a rear elevational view thereof;
 FIG. 3 is a side elevational view thereof, the opposite side being identical;
 FIG. 4 is a top view thereof;
 FIG. 5 is a bottom view thereof;
 FIG. 6 is a fragmentary sectional view taken along the lines 6—6 of FIG. 1; and
 FIG. 7 is a fragmentary sectional view taken along the lines 7—7 of FIG. 3.
 The scalloped ribs are evenly spaced around the entire periphery of the bottle.
